UNITED STATES PATENT OFFICE

129,107

DESIGN FOR A SLIP

Emil Samek, New Rochelle, N. Y., assignor to Tailored Silk Undergarment Co. Inc., New York, N. Y.

Application May 17, 1941, Serial No. 100,998

Term of patent 14 years

To all whom it may concern:

Be it known that I, Emil Samek, a citizen of the United States of America, residing at 80 Oxford Road, New Rochelle, county of Westchester, and State of New York, have invented a new, original, and ornamental Design for a Slip, of which the following is a specification, reference being had to the accompanying drawing, forming a part thereof.

Fig. 1 is a rear view of a slip showing my new design.

Fig. 2 is a front perspective view thereof.

I claim:

The ornamental design for a slip, as shown.

EMIL SAMEK.
